(57) **CLAIM**

The ornamental design for an instrument and utensil for medical or laboratory diagnosis, as shown and described.

DESCRIPTION

1. Instrument and utensil for medical or laboratory diagnosis
2. Instrument and utensil for medical or laboratory diagnosis

1.1 : Perspective

1.2 : Front

1.3 : Back

1.4 : Left

1.5 : Right

1.6 : Top

1.7 : Bottom

2.1 : Perspective

2.2 : Front

2.3 : Back

2.4 : Left

2.5 : Right

2.6 : Top

2.7 : Bottom

The broken lines illustrate portions of the instrument and utensil for medical or laboratory diagnosis which form no part of the claimed design.

1 Claim, 14 Drawing Sheets
